UNITED STATES PATENT OFFICE.

GEORGE J. CRAIGEN, OF NEW YORK, N. Y.

BRICK AND OTHER LIKE MACHINE.

Specification of Letters Patent. Patented Oct. 15, 1918.

1,281,298.

Application filed September 16, 1913. Serial No. 790,039.

To all whom it may concern:

Be it known that I, GEORGE J. CRAIGEN, of the city of New York, borough of Brooklyn, county of Kings, State of New York, 5 have invented new and useful Improvements in Brick and other like Machines, of which the following is a full, clear, and exact description, reference being had to the accompanying drawings, forming a portion of 10 this specification.

This invention relates to machines in which bricks and analogous articles are made and in which molds, pallets and ejectors or equivalent means adapted to do similar work are employed; and it consists in the 15 combinations, constructions, and arrangements of parts hereinafter described and shown in the specification and pointed out in the claims.

20 This invention has for its objects the improvement in the manufacture of brick and analogous articles; increasing the percentage of perfect articles made, thereby cheapening the cost of manufacture; lessening the 25 amount of manual labor heretofore required and employed in operating the machine and handling the articles thus made; and in the improved manipulations of the "pallets" 30 relatively to the molds and ejector mechanism over that heretofore practised.

The embodiments of my invention illustrated in the accompanying drawings are 35 illustrative of the principles thereof. Referring to these drawings, Figure 1 is a side elevation of portions of one form of brick machine with the pallet conveyer shown in cross section arranged near the end of the fixed bed, just underneath the ejector mechanism and adjacent to the line of travel of the 40 molds over such bed, and the mechanism for moving the pallets to and from the molds to receive the brick or other structures while being ejected therefrom. Fig. 2 shows in side elevation the pallet conveyer and its operating mechanism combined with the brick machine, seen in elevation in Fig. 1, in end elevation. Fig. 3 shows in plan view a portion of the mechanism for operating the pallet conveyer in unison with the operation 50 of the brick machine. Fig. 4 shows the bar of the scoring device seen in Fig. 1. Fig. 5 shows in plan view a portion of the molds seen in Fig. 1. Fig. 6 shows in plan view the preferred arrangement of the conveyer 55 relatively to the brick machine. Fig. 7 shows in side elevation a portion of the

conveyer arranged in a somewhat modified way relatively to the ejector mechanism of a brick machine wherein the portions of the conveyer which receive the pallets are moved 60 into position relatively to the molds for the pallets to receive the brick or other structures as they are ejected therefrom. Fig. 8 shows another arrangement of pallet conveyer, mold and ejector mechanism wherein 65 the pallet is not moved relatively to the mold while the bricks are being ejected therefrom.

In Figs. 1 and 2, A represents one form of a brick machine having a material feed 70 chamber A¹, and mold filling mechanism A², operating therein and a series of molds A³, with mold operating mechanism A⁴, by which the molds are preferably intermittently moved to and away from the material 75 feed chamber A¹. The construction of the brick machine here shown is generally of a form known in the art wherein the molds are connected together so as to form an endless chain or belt which passes over the 80 octagonal pulleys O, O, suitably mounted in the main frame of the machine. These molds A³, A³, &c., are preferably caused to pass over and to contact with a fixed bed piece or plate X, preferably hollow into 85 which heating material can be introduced so as to more or less heat the same and thereby more or less heat the material in the molds as it passes on to the point where it is ejected 90 therefrom in the form of bricks or other articles. One of the octagonal pulleys O is driven by the ratchet wheel o, seen at the left of Fig. 1, and the pawl o' and the connected parts o², o², &c., which connect such pawl to the main driving wheel or shaft Z of 95 the machine. This construction of brick machine is preferably provided with means by which the material in the molds is repressed before being ejected therefrom. The machine shown in the drawings is provided 100 with a combined repressing and ejecting means arranged in juxtaposition to the line of travel of the molds and the end of the stationary bed X by which the molded or formed brick in one mold is repressed and 105 such repressed brick in another or preceding mold is ejected at each complete movement of the reciprocating head of the ejecting means, which is provided with suitable devices to simultaneously act on the brick in 110 two molds at the same time, as explained below. This mechanism consists of two

parts simultaneously movable, *a* and *b*, respectively, which are fixedly secured to a movable head *B*², movable upwardly and downwardly in a fixed frame *B*³, by operating mechanism *B*⁴ suitably connected to the main driving parts of the brick machine as seen in Fig. 1. The material in the molds that are in position to register with the head *B* and parts *a* and *b* attached thereto is operated upon at each downward movement of such head and parts. The conveyer *C* receives and conveys the pallets from where received to and away from the molds and is preferably arranged at substantially right angles to the movement of the chain or belt to which the molds *A*³, *A*³, &c., are secured, as seen in Fig. 6. This conveyer preferably consists of two link chains *C*¹, *C*¹, which are connected together by rods having a roller or other suitable bearing at each end to engage with a suitable support *X*¹ by which the pallets *E*, *E*, &c., carried by the conveyer are held in operative relation to the brick machine. These link chains *C*¹, *C*¹, are preferably composed of links of uniform dimensions adapted to be mounted on the octagonal pulleys *c*, *c*, as seen in Fig. 2 which are suitably mounted on the frame *Y* of the conveyer.

30 The pallet conveyer link chains *C*¹, *C*¹, are caused to move a distance equal to something more than the length of the pallet into position relatively to the molds, from which the pallets are to receive the bricks or other structures, as ejected therefrom, by means of the pawl *D* which engages with the chains as seen at the right of Fig. 2, and is connected to the main driving part *Z* by connecting links *d*, *d*, *d*, *d*, *d*, shaft *d*¹, and the arms thereon arranged as shown. This conveyer belt or chain is adapted to receive the pallets, as they may be fed to it, and be carried the proper distances into position relatively to the molds to receive the bricks or other structures as the same are ejected therefrom.

50 In this preferred construction means are provided by which the pallets, carried by the conveyer, are moved individually toward and away from the molds when they are brought into position to receive the bricks or other structures, as the same are ejected therefrom. This movement causes the pallets to close the open side of each mold as it is brought into position for the ejector to operate and remove the compressed material therefrom. This movement is caused to take place by means, which consist of two parts *H*, *H*, movable upwardly and downwardly, as the pallets are to be moved, in a suitable frame attached to the conveyer mechanism. One end of each of these parts is adapted to engage with a pallet, as it is to be moved to close the open side of the mold.

55 The other end of each of these parts *H*, *H*, is

connected to a link *H*¹, *H*¹, between the ends thereof, as seen in Fig. 1. These links *H*¹, *H*¹, are at one end pivotally mounted to the frame of the machine, the other ends being similarly attached to one end of each of the links *H*², *H*². These links have their other ends pivotally attached to the lower end of the arms of the rock shaft *H*³. This rock-shaft *H*³ has an arm *H*⁴ to which is attached one end of a link *H*⁵ the other end of which is connected with the main driving part *Z*. All of these several parts are so proportioned and constructed that when the pallet is brought into position to receive the brick from the mold they coöperate with molds, ejector mechanism and with one another to receive the brick from the molds as follows: The parts *H*, *H*, will engage with the pallet and move it toward the mold and close the same, ready to receive the brick or other structures as the same are ejected from the mold. About the time the pallet has closed the mold, the part *b* of the ejector mechanism starts toward the mold and comes into contact with the material therein to eject it therefrom. From the time this part *b* comes into contact with the material to eject it from the mold the part *b* and the parts *H*, *H*, move preferably at the same speed and to the same extent or in substantial unison one with the other during the operation of ejecting the material and depositing the pallet on the conveyer, with the material thereon, in position to be carried on toward the point where the same is to be removed from the conveyer and placed on the car to be taken to the drying room or other desired point in the works.

By this movement in unison of the parts named in the preferred construction shown the material is held in place and ejected from the molds and deposited on the pallet with little or no danger of being disturbed or distorted in form, thereby increasing the proportion of perfect brick or other structures formed and delivered by the machine.

If desired a scoring device as I may be attached to the hollow bed plate of the brick machine, as seen in Figs. 1 and 4, by which one side of the brick or other structures may be scored or grooved to receive the mortar when laid up in a wall. This scoring device as I consists of a bar *I*¹ having projections seen in Fig. 4 of the drawings. This bar is preferably arranged at the end of the bed plate *X* and at substantial right angles to the path of movement of the molds through the machine, it being preferably yieldingly mounted, as shown. This bar *I* is preferably mounted on the free ends of two levers *I*², *I*², arranged on opposite sides of the bed plate *X* to which one end thereof is pivotally attached as shown. The springs *I*³, *I*³, which yieldingly hold this device in operative position relatively to the molds

containing the compressed material are preferably secured in place, as shown. Pins i , i , &c., are secured to the sides of the links to which the molds are attached, as seen in Fig. 5 1, which coöperate with the cam surfaces formed on the upper edges of the pivoted levers I^2 , I^2 , to move the scoring bar I^1 which is attached to the free ends of levers I^2 , I^2 , to move such bar out of scoring position 10 and out of contact with the molds as they pass by the scoring device. The bed or hollow support X is preferably supplied with rollers or other suitable means x , x , &c., for holding the molds A^3 , A^3 , into desired contact with the hollow bed plate X . This hollow bed X is preferably provided with suitable pipes and valves, for connecting such bed with a supply of steam, as shown at P , P near the ends thereof, for heating the 15 same and more or less heating the molds and material therein, thus preventing adhesion of such material as it passes over such bed.

Instead of moving the pallet alone toward and away from the mold to close and open 20 the same to receive the brick or other structures therefrom, as shown in Fig. 2, the conveyer chains, with the pallet thereon, may be moved toward and away from the molds to close and open the same, as shown in Fig. 7.

30 If desired the partial heating of the material may be omitted and the conveyer used in operation with the mold filling chamber, the compressing and ejecting mechanism, as the same is sometimes shown in the prior art, 35 and as illustrated in Fig. 7 of the drawings. The general arrangement of filling chamber, compressing and ejector mechanism is well known in the art and does not need any detailed description herein to be fully understood. Also, if desired the repressing the 40 brick a second time may be dispensed with and without in any way changing the coöperation of the pallet conveyer with the ejector mechanism of the machine, as will 45 be manifest to those skilled in this art.

If desired, the means shown in Figs. 1, 2 and 3 and described herein for moving pallet toward and away from the mold to close and open the same may, when slightly modified, be used for moving pallet and chain 50 links C^1 , C^1 , toward and away from the mold, or any other desired form of mechanism may be used for this purpose.

The construction thus shown may have 55 the moving parts H , H , so changed that instead of engaging directly with the pallet alone that they be made to engage directly with the chain links themselves, so as to move such links and pallet bodily to close 60 and open the molds. These parts H , H , seen in Fig. 2 are H^{10} , H^{10} , in Fig. 7. It is believed unnecessary to further describe this mechanism in detail that is indicated in Fig. 7 in order that it be fully understood.

65 Or when the material is of a nature to be

compressed and remain in the compressed form and remain intact during the operation of being ejected from the molds, the closing and opening of the molds may be dispensed with and the pallet conveyer be 70 advantageously used without the pallet being moved toward and away from the molds, as shown in Fig. 8, wherein the chain links C^1 , C^1 may be arranged a sufficient distance away from the molds to permit the 75 pallet and brick upon the same to freely pass by them as the pallet is conveyed away therefrom to the point where the pallet with the brick upon it, is to be removed from the machine. When so arranged the pallet may 80 remain stationary, or nearly so, when receiving the brick or other structures upon being ejected from the molds. In such a case the parts H , H , and H^{10} , H^{10} and the 85 mechanism by which they are operated is dispensed with, the coöperation of the conveyer with the mold and ejector device being substantially the same, so far as concerns the feeding of the pallets into the machine 90 to receive the brick and convey them to the point where the same are to be removed.

The operation of brick machines of the general class herein shown is well known to those skilled in this art. Consequently, it is only necessary to describe the operation 95 of the conveyer in connection with the general class of machines shown. The conveyer and operating mechanism, as shown, is so combined with a machine having means for ejecting brick or analogous articles from the 100 molds that the conveyer operates intermittently in unison with the intermittent movement of the molds. Consequently, the endless conveyer chains or belt may, as seen in 105 Figs. 1, 2 and 8, remain substantially stationary while the pallets receive the compressed material as the same is ejected from the molds after being formed or shaped therein. As shown in Fig. 7 the conveyer chains or belt, as before explained, are 110 moved toward and away from the molds and cause the pallets to correspondingly move to close and open the molds while the material is being ejected therefrom. At each revolution of the wheel or shaft Z of the brick 115 machine the bar or link d^2 and rock shaft d^1 with the links or connections d , d , &c., the pawl D is caused to take on a forward and backward movement and as the free end of this pawl engages with the chain links 120 C^1 , C^1 , as it starts forward, such chains or belt is moved forward a little more than the length of a pallet as E see Fig. 2, into position to receive the brick or similar articles as they are ejected from the molds. During 125 the backward movement of the pawl D it is brought into position to again engage with the chains C^1 , C^1 , or belt ready to move the same a distance forward to bring another pallet into position to receive the brick from 130

another mold. When the pallet is thus brought into position the pallet, as seen in Figs. 1, 2 and 7, is moved into position for it to close the mold by the operation of the parts H, H, and H¹⁰, H¹⁰ through means of the links or parts as they are moved by the oscillation of the levers H¹, H¹, through their being connected with the cam which moves as the main wheel or shaft Z moves, when it is in motion, by means of the connecting parts H², H², H³, H⁴, and H⁵, co-operating with such cam. As seen in Figs. 1 and 2, the parts H, H, engage directly with the pallet to close and open the mold, while in Fig. 7 the parts H¹⁰, H¹⁰, engage directly with the chains C¹, C¹ and move the pallet upon them to close and open the mold. I have shown and described that different combinations of parts having specific characteristics and different specific constructions or forms of parts may be used in the place or places of some that are herein shown without in any way changing the character or coöperative relations of the parts of such combinations, as must be manifest to a mechanic, and therefore, I do not wish to be limited to the specific forms and constructions of parts herein shown, but wish to include each and all that are within the spirit of my invention.

What I claim as new is:—

1. In a machine having molds open on opposite sides, a stationary bed over which

Copies of this patent may be obtained for five cents each, by addressing the "Commissioner of Patents, Washington, D. C."

the molds move, pressing and ejecting means for forming brick and analogous articles, 35 the combination, substantially as described, of a pallet conveyer arranged adjacent to the stationary bed adapted to receive and convey pallets into register with the ejector means and means adapted to engage directly 40 with the pallet received by the conveyer and move it independently of the conveyer toward and away from the mold to close the same to receive the formed brick and return the pallet to the conveyer. 45

2. In a machine having movable molds open at top and bottom, pressing and ejecting mechanisms movable toward and away from the top portion of the molds for forming brick and analogous articles, the combination, substantially as described, of a bed or support over which the molds move into register with the ejector mechanism, movable scoring means constructed and arranged to enter the mold, and means adapted to move the scoring means into that side of the mold opposite to that at which the ejector enters to score or roughen one side of the contents thereof. 55

In testimony whereof, I have signed my 60 name to this specification in the presence of two subscribing witnesses.

GEORGE J. CRAIGEN.
